(57) **CLAIM**

The ornamental design for a battery as shown and described.

DESCRIPTION

FIG. 1 is a front, right, and top perspective view of a battery in accordance with our new design;

FIG. 2 is a rear, left, and bottom perspective view of a battery in accordance with our new design;

FIG. 3 is a front elevational view of the battery in accordance with our new design;

FIG. 4 is a rear elevational view of the battery in accordance with our new design;

FIG. 5 is a top plan view of the battery in accordance with our new design;

FIG. 6 is a bottom plan view of the battery in accordance with our new design;

FIG. 7 is a right side elevational view of the battery in accordance with our new design; and,

FIG. 8 is a left side elevational view of the battery in accordance with our new design.

The broken lines in the drawings illustrate portions of the battery which form no part of the claimed design.
